UNITED STATES PATENT OFFICE.

JOHN CHRISTOPHER SUMNER, OF PRESTON, ENGLAND.

DEVICE FOR WASHING DRINKING-TUMBLERS AND THE LIKE.

1,176,497.

Specification of Letters Patent. Patented Mar. 21, 1916.

Application filed July 13, 1915. Serial No. 39,602.

To all whom it may concern:

Be it known that I, JOHN CHRISTOPHER SUMNER, a subject of the King of England, residing at Preston, in Lancashire, England, 5 have invented certain new and useful Improvements in Devices for Washing Drinking-Tumblers and the like, of which the following is a specification.

This invention is for improvements in or 10 relating to devices for washing drinking tumblers and the like and belongs to the type of scrubber having a central conical mop adapted to fit the interior of the tumbler, and external scrubbing-elements which 15 are hinged at their ends about the central scrubber and are urged forward toward the central scrubber by an elastic band. By thrusting the tumbler over the central scrubber or mop and between the outer 20 scrubbers and then rotating either the tumbler or the scrubber, the interior and exterior could be simultaneously cleaned.

A scrubber according to the present invention is provided with hinged scrubbing-elements surrounding the central mop, the 25 said elements constituting the external wall of the scrubber, so that they can be swung out flat for cleaning purposes.

One of the difficulties in the forms of 30 scrubbers heretofore employed is that the scrubbing-elements surrounding the mop cannot be got at satisfactorily for cleaning them, but this difficulty is overcome by the construction hereinafter described.

35 In the accompanying drawings:—Figure 1 is a perspective view of a scrubber constructed according to one method of carrying out this invention; Fig. 2 is a perspective view of the same scrubber with the 40 parts opened out for cleaning, and Fig. 3 is a side elevation of a scrubber constructed according to a modified method of carrying out the present invention.

The central scrubbing - element conveniently takes the form of a cylindrical wooden plug A which is secured to a base B, for example by providing it with a screw-threaded metal stem A¹ which engages a correspondingly threaded metal socket B¹. The 45 plug A is provided over the whole of its exterior with bristles so that it constitutes a brush which is approximately cylindrical in form and at the top is rounded. This brush is of such dimensions as to fill the interior 50 of the tumbler or other article that it is intended to scrub, and may be variously

shaped according to the interior shape of such article, that shown in the drawings being intended for cleaning tumblers having the bottom rounded on the inner side. 60

The exterior scrubbers take the form of segmental bodies C which may be of wood charged with bristles C¹. The operative side of each external scrubbing-element is shaped approximately to fit flush against an 65 approximately cylindrical surface and as many of these may be employed as is found convenient, four being shown in the drawings mounted equidistant around the central scrubber A. Each scrubber C is secured 70 to the base by a hinge C² and the upper ends of the scrubbers are grooved at C³ to receive an elastic band D. When the elastic band is removed they can be opened out as shown in Fig. 2, so that all parts can be 75 cleaned, and when the band is in position, they are drawn together toward the central scrubber, so that when a tumbler is pushed in, as shown at E, they are forced back 80 against the yielding control of the elastic band D and thus bear against the exterior of the tumbler, while the bristles on the inner brush A bear against the interior of the same; thus by rotating the tumbler by 85 hand it is scrubbed inside and out simultaneously.

Scrubbers have been proposed for simultaneously cleansing the inside and the outside, but the outside scrubbing-elements have been fixed relatively to the inside one and 90 thus if a tumbler was rather too large, or was a little carelessly handled, it was broken between the unyielding scrubbing-elements, whereas the scrubber arranged as described 95 yields to the tumbler, so that even if this is not put on quite true to the central element it is not broken easily, and, moreover, the yielding-control insures that the scrubbers are kept up to their work on all sides of the 100 tumbler.

It will be seen that in the construction shown in Figs. 1 and 2, the lower ends of the scrubbers C being hinged to the base cannot move very freely relatively to the central scrubber A. In Fig. 3 an arrangement of scrubbers F is shown, whereby each scrubber can move bodily to and from the central scrubber. Each scrubber F is carried by a U-shaped member or a stirrup G whose ends are bent outward at G¹ to form a mouse-trap 105 spring and the extreme ends are driven into or otherwise secured to the base H at G². 110

The looped end of each stirrup G is secured to the scrubber by a strap J within which it freely hinges. It will be seen that each of these scrubbers can tilt about the bend of the 5 stirrup G, so that the base can lie out farther from the central brush than the upper end when used with an article such as a tumbler the bottom end of which is usually of smaller diameter than the upper end; the spring 10 ends G¹ of the stirrup, moreover, afford the yielding means whereby each external scrubber is urged toward the central scrubber.

It will be appreciated that the scrubbing-elements need not be provided with bristles, 15 as any suitable rubbing surface may be provided on them such as a pad of wash-leather. The invention, moreover, is not restricted to the washing of tumblers, as lamp chimneys or any circular article which provides comparatively plain exterior and interior surfaces could be cleaned by such a device, the 20 device being shaped according to the work it is intended to do.

Although "scrubbing" has been referred to 25 throughout the specification, it will be understood that this does not necessarily mean scrubbing by means of bristles, as any kind of rubbing surface may be employed for the purpose, according to the character of the 30 cleaning which is desired.

What I claim as my invention and desire to secure by Letters Patent is:—

1. In a scrubber for circular articles the combination of, a base, a central mop carried 35 thereon, a series of surrounding scrubbers having their scrubbing faces toward the mop,

means for hinging each scrubber relatively to the base in such manner that the scrubber can be swung out flat for cleaning purposes, and means for urging the scrubbers 40 yieldingly toward the central mop, substantially as set forth.

2. In a scrubber for circular articles the combination of, a base, a central mop carried thereon, a series of surrounding scrubbers 45 having their scrubbing faces toward the mop, means for hinging each scrubber relatively to the base in such manner that the scrubbers can be swung out flat for cleaning purposes, and yielding means for always urging 50 the upper ends of the hinged scrubbers toward the central mop, substantially as set forth.

3. In a scrubber for circular articles the combination of, a base, a central mop carried 55 thereon, a series of surrounding scrubbers having their scrubbing faces toward the mop, means for hinging each scrubber relatively to the base in such manner that the scrubbers can be swung out flat for cleaning purposes, 60 and a resilient band (D) surrounding the upper ends of the hinged scrubbers so that these are always urged yieldingly toward the central mop, substantially as set forth.

In testimony whereof I have signed my 65 name to this specification in the presence of two subscribing witnesses.

JOHN CHRISTOPHER SUMNER.
